UNITED STATES PATENT OFFICE.

SIDNEY VOLK, OF BENTON HARBOR, MICHIGAN.

SKYLIGHT.

Application filed May 1, 1925. Serial No. 27,251.

My invention relates generally to improvements in skylights, more particularly to a skylight which has a metallic frame and is of fire-proof construction, and it consists in 5 the combinations, constructions and arrangements herein described and claimed.

An object of the present invention is the provision of a skylight of the character described having a frame comprising a plurality of 10 detachably connected members adapted to be easily and quickly assembled and secured in place without the use of any special tools or the exercise of any unusual skill.

A further object of the invention is to provide 15 a skylight of the character described in which the respective members of the frame brace one another so that a strong and durable unitary structure will be provided when the frame members are secured to one another in assembled position.

A further object of the invention is the provision of a skylight having adequate facilities for the drainage of condensate or other moisture therefrom.

Other objects and advantages will be apparent 25 from the following description, considered in conjunction with the accompanying drawings, in which

Figure 1, is a plan view of the improved 30 skylight, with the glass panels for half the skylight omitted,

Figure 2, is a transverse vertical section through the skylight,

Figure 3, is a perspective view, showing a 35 clip and securing means for fastening the ridge cap to the ridge bar of the skylight,

Figure 4, is a view similar to Figure 3, showing a clip and a securing element for fastening one of the inclined sash bars to a 40 covering strip,

Figure 5, is a relatively enlarged fragmentary vertical sectional view, showing the construction of the central portion of the skylight, and

Figure 6, is a view similar to Figure 5, showing the construction of an end edge portion of the skylight.

The improved skylight has a frame structure including an endless base or eaves bar, 50 a ridge bar, and a plurality of spaced inclined sash bars which connect and stay the base bar and the ridge bar to each other and cooperate with the base bar and ridge bar to support the glass panels of the skylight.

The base bar is shown as having substantially the form of a rectangle and as com-

prising a pair of parallel side members 1, and a pair of parallel end members 2, the end members being disposed at right angles to the side members and meeting end portions of side and end members of the base bar being secured rigidly together, as by one 50 of such meeting end portions being formed with an attaching extension as indicated at 3 in Fig. 2, bent flatwise against and secured 65 by a rivet 4 or like fastening device to the other meeting portion. Each side member and each end member of the base bar preferably is formed of a strip of metallic material bent along lines extending longitudinally of the strip so that the member will 70 comprise an upright channel shaped upper portion as indicated at 1^a, for each side member 1 and at 2^a for each end member 2 and a vertical lower flange portion as indicated at 1^b for each side member 1 and at 2^b for each end member 2. The flange portions 75 1^b of the side members 1 are shown in Fig. 2 as being provided with the hereinbefore mentioned attaching extensions 3.

The inner flange of the upper portion of each member 1 or 2 is inclined inwardly and upwardly as shown in Figs. 2 and 6 and is of double thickness. The bottom or web of the upper portion of each member 80 1 or 2 also is of double thickness from its juncture with the inner upper flange of the member to the plane of the depending lower flange of the member and then is formed of but one thickness of the hereinbefore mentioned metallic strip for the remainder of its width which is a slight distance and extends outwardly from the plane of depending lower flange of the member.

The outer flange of the upper portion of each member 1 or 2 extends vertically from its juncture with the bottom of the member to the approximate level of the upper edge of the upwardly and inwardly inclined inner upper flange of the member and then 90 is bent downwardly and outwardly as indicated at 1^c for a member 1 and at 2^c for a member 2. Each portion 1^c or 2^c of the outer upper flange of each member 1 or 2 is provided at its outer end with an upturned 100 lip 1^d or 2^d. Each portion 1^c or 2^c of each member 1 or 2 is substantially parallel to the upwardly and inwardly inclined inner upper flange of that member.

The ridge bar preferably is formed of 110 two similar channel shaped metallic members 5 and 6 respectively, arranged with the

web portions thereof vertically edgewise and secured flatwise against each other by bolts and nuts as indicated at 7 in Figure 2, or like fastening devices. The upper flanges 5 of members 5 and 6 are inclined downwardly and outwardly as indicated at 5^a and 6^a respectively. The lower flanges of the members 5 and 6 of the ridge bar likewise extend downwardly and outwardly from their junctures with the web portions of such members as indicated at 5^b and 6^b respectively.

Each inclined sash bar comprises a pair of metallic channel members 8 and 9 respectively, arranged with the web portions thereof secured flatwise against each other by rivets 10 and disposed vertically edgewise, the outwardly extending upper flanges of the members of each inclined sash bar being indicated at 8^a and 9^a respectively, and the outwardly extending lower flanges of the same members being indicated at 8^b and 9^b respectively.

Each inclined sash bar is formed with the lower end portion thereof adapted to be received in the channel shaped upper portion of one of the end members 2 or side members 1 of the base bar and to extend transversely of the channel shaped upper portion of that base member with the upper flanges 8^a and 9^a of the sash bar in abutting relation of their lower ends with the downwardly inclined portion 2^c or 1^c of the base member 2 or 1 as the case may be, the flanges 8^a and 9^a of the sash bar lying in the plane of the portion 2^c or 1^c of the base member and the lower end portions of the flanges 8^b and 9^b of the sash bar resting upon the upwardly and inwardly inclined inner upper flange of the base member. The web portions of each inclined sash bar have laterally turned attaching lugs 11 secured by bolts and nuts 12 or like fastening devices to the outer upper flange of the base member with which that particular inclined sash bar is in abutting relation at its lower end.

The inclined sash bars may vary in length as required, according to the position of each sash bar as a connector between the ridge bar and the endless base bar. Each side member 1 of the base bar may be connected with the ridge bar by a pair of spaced inclined sash bars having the construction hereinbefore described. Each side sash bar has the upper end portion thereof extended between the flanges 5^a and 5^b, or 6^a and 6^b of the ridge bar as clearly shown in Figure 2, and is provided with laterally turned attaching lugs as at 13 in Figure 5, the corresponding attaching lugs 13 of oppositely extending side sash bars being secured to each other and to the web portion of the ridge bar by bolts and nuts 14 or like fastening devices. Corner sash bars extend from the corners of the base bar to the end

portions of the ridge bar and are secured to the latter in the same manner as the side sash bars.

Each end sash bar extends from the end members of the base bar to the ends of the ridge bar. Each end sash bar has the lower flanges of the outer end portion thereof secured by bolts and nuts 15 (see Figure 2) to the inner upper flange of the base member 2 with which that end sash member is associated.

A glass panel 16 is disposed between the side sash bars at each side of the skylight frame. Glass panels 17 and 18 are disposed at each side of the skylight frame and other glass panels 19 and 20 are disposed between adjacent corner and end sash bars at each side of the longitudinal median line of the skylight frame. Only the glass panels for a longitudinal half portion of the skylight frame are shown in the drawings (see Figure 1), but it will be obvious that corresponding glass panels are provided for the remaining half portions of the skylight frame. Figure 2 illustrates how each glass panel 16 is mounted and it is thought that the description thereof will suffice as a description of the mountings of each of the remaining glass panels as well.

The glass panel 16 has the lateral edge portions thereof resting upon and spaced from the adjacent flanges of the two supporting side sash rails by a layer 21 of putty or like fireproof binding and cushioning material. The upper flanges of each sash bar preferably curved upwardly slightly at their outer edges as shown in Figure 4 to provide a seat for the layer of putty. The lower end of the glass panel 16 abuts lip 1^d of one of the side members of the base bar.

The upper end portion of the glass panel extends close to the adjacent upper flange of the ridge bar and underneath the adjacent lateral edge portion of a metallic ridge cap 22 which is of substantially inverted V-shape in cross sectional contour. A layer of putty 23 is clamped upon the upper flanges of the ridge bar and the upper end portions of the glass panels by the ridge cap. The latter is secured to the ridge bar by clips 24, each of which has lateral hooked portions 24^a adapted to engage with edge portions of the upper flanges of the ridge bar, the middle portion of each clip having an opening through which the shank of a bolt 25 extends through the layer of putty 23 and through an opening in the ridge cap, a nut 26 being in threaded engagement with the upper end portion of the bolt 25 and being tightened against the ridge cap to hold the latter in place. Each inclined sash bar supports the adjacent lateral edges of adjacent glass panels and each inclined sash bar carries a strip 27 for clamping a covering layer

of putty, such as indicated at 28 in Figure 5 upon the adjacent edge portions of adjacent glass panels. The upper ends of the respective clamping strips 27 extend beneath the ridge cap 23 which is closed at its ends as indicated at 30 in Figure 1. Each strip 27 is arched transversely as shown in Figures 5 and 6 and is secured to the underlying sash bar by a plurality of sets of fastening devices, each of which comprises a clip 31 adapted to engage with the flanges at the upper end of the underlying sash bar, a bolt 32 having the shank extended through an opening in the clip 31, the layer of putty 28 and an opening in the crown portion of the clamping strip and a nut 33 in threaded engagement with the upper end portion of the nut and tightened against the clamping strip 27 to secure the latter in place.

Each sash bar has an opening as indicated at 34 at the lower edge of the portion thereof that is received in the channel shaped upper portion of a member of the base bar so that condensate or other moisture can pass along the channel shaped upper portion of the base bar and drain from the latter through drain outlet openings 35.

The glass panels preferably are made of so-called "wire glass".

The skylight constructed in the manner just described will be strong, durable and fireproof. The pendent lower or rim flange of the base bar is adapted to fit in any casing or opening of suitable size. No unusual skill or experience is required to assemble the skylight or to install it in an opening or casing of suitable size.

Obviously the invention is susceptible of embodiment in forms other than that which is illustrated in the accompanying drawings

and I therefore consider as my own all such modifications and adaptations thereof as fairly fall within the scope of the appended claims.

I claim:

1. In a skylight, a metallic frame comprising a base bar, a ridge bar, spaced inclined sash bars extending between the ridge bar and the base bar, and glass panels extending between the ridge bar and base bar and each having the lateral edge portions thereof supported upon adjacent sash bars, said sash bars having oppositely extending glass panel supporting flanges at their upper edges, said flanges having the outer edges thereof turned upward to retain putty on said flanges underneath the overlying edge portions of said glass panels.

2. In a skylight, a metallic frame comprising an endless base bar, a ridge bar, spaced inclined sash bars extending between the ridge bar and the base bar, and glass panels extending between the ridge bar and base bar, a clamping strip for each inclined sash strip, and means adjustably connecting the clamping strip with its sash strip so that the clamping strip will cover the sash strip, a layer of non-inflammable binding material between the upper surface of each sash bar and the edge portions of the glass panels on the sash bar, said sash bar having upwardly turned portions at the edges of the upper surface of the sash bar to prevent lateral displacement of said layer of binding material, and a layer of non-inflammable binding material clamped between said clamping strip and the edge portions of the glass panels therebeneath.

SIDNEY VOLK.
